5 Claims. (Cl. 310—8.7)

This invention relates to apparatus for transforming electrical energy to sound energy. More particularly, this invention relates to the use of piezoelectric or electrostrictive materials such as quartz or barium titanate in association with metals for effecting the transformation of radio frequency electrical energy to sound energy.

It is an object of this invention to provide a transducer for effecting the transformation of electrical energy to sound energy wherein the quantity of piezoelectric or electro-strictive material required to produce the desired resonance is reduced to a minimum.

It is another object of this invention to provide a transducer for effecting the transformation of electrical energy to sound energy wherein only metal is positioned at the nodal zone thereof, thereby producing a very durable transducer which is, for all practical purposes, shock proof since breakage of the piezoelectric or electro-strictive material as a consequence of normal stress at the nodal zone during operation is thereby avoided.

It is another object of this invention to provide a transducer for effecting the transformation of electrical energy to sound energy wherein no electrical leads whatever are connected directly to the surface electrodes of the piezoelectric or electro-strictive material.

It is another object of this invention to provide a transducer for effecting the transformation of electrical energy to sound energy wherein the sonic frequency or resonance may be varied over wide ranges while utilizing the same quantity of piezoelectric or electro-strictive materials by merely changing the thickness of the metal components thereof.

It is another object of this invention to provide a transducer for effecting the transformation of electrical energy to sound energy which may be produced at a much lower cost than other transducers made only of piezoelectric or electro-strictive materials heretofore used to perform the same function.

It is another object of this invention to provide a transducer for effecting the transformation of electrical energy to sound energy in which the driving impedance thereof is much lower than the driving impedance of any solid block of piezoelectric or electro-strictive materials heretofore used which is of the requisite size to perform the same function.

It is another object of this invention to provide a transducer for the conversion of radio frequency electrical energy into sound energy wherein the radio frequency voltage required to drive said transducer is much lower than the corresponding voltage required to drive a solid block of piezoelectric or electro-strictive materials heretofore used to perform the same function.

It is another object of this invention to provide a transducer for effecting the transformation of radio frequency electrical energy to sound energy in which component failure due to dielectric breakdown and leakage due to dirt and chemical deposits, and the like, which frequently form on the surface of such transducers when operated in the presence of plant atmosphere, are reduced to a minimum.

It is another object of this invention to provide a transducer for converting electrical energy into sound energy which may be constructed to produce a variety of fre-

2

quency ranges and to provide any size radiating area desired.

Other objects and attendant advantages will become apparent hereinafter and in the drawings wherein:

5 FIG. 1 is an exploded view of a transducer as provided in accordance with this invention;

FIG. 2 is a plan view of a transducer at one stage of its construction;

FIG. 3 is a cross-sectional view of a transducer taken 10 as indicated by the lines and arrows III—III of FIG. 2;

FIG. 4 is a view partly in perspective and partly in cross-section showing one specific arrangement of a transducer as provided in accordance with this invention;

15 FIG. 5 is a diagrammatic representation of the operation of a transducer as provided in accordance with this invention;

FIG. 6 is a view partly in perspective and partly in cross-section of a modification of the transducer as provided in accordance with this invention;

20 FIG. 7 is an exploded view similar to FIG. 1, illustrating a modified form of transducer, as provided in accordance with this invention; and

25 FIG. 8 is a view in plan similar to FIG. 2 of the modified transducer illustrated in FIG. 7.

The following description is directed to the specific form of the invention as shown in the drawings and is not intended to be addressed to the scope of the invention as exemplified thereby. It will be appreciated that the drawings represent preferred embodiments of the invention which is capable of being practiced in a wide variety of forms and arrangements.

Adverting herewith to the specific form of the invention illustrated in the drawings, the numeral 10 designates a relatively thin metallic membrane to which is secured by spot welds 11a and 11b and by copper brazing 11c a solid metal block of steel 12 at the center of which there is provided a threaded hole 13 extending through the width of the block. Disposed upon the upper face 14 of the metal block 12 are barium titanate discs 15a, 15b, 15c and 15d.

35 Thin electrodes of silver metal 16a, 16b, 16c and 16d and 17a, 17b, 17c and 17d are secured to the upper and lower surfaces of the discs 15a, 15b, 15c and 15d, respectively.

Disposed upon the upper surface of the barium titanate

35 discs 15 is another solid block of steel 19 having a central bore 20 extending therethrough at the center thereof. While the length and breadth of the metal block 19 are equal to the length and breadth of the metal block 12, the thickness or width of the block 19 is preferably only about two-thirds that of the block 12. To the surface of

50 one side 21 of the metal block 19 there is attached a metal conductor lug 22 which is secured to side 21 by means of a straight metal drive screw 23 in a manner so as to make good electrical contact between the lug 22 and the metal block 19. On the top surface 25 of the block

55 19 are disposed barium titanate discs 26a, 26b, 26c and 26d. In like manner as before, thin electrodes of silver metal 27a, 27b, 27c, 27d and 28a, 28b, 28c and 28d are affixed to the upper and lower surfaces respectively of the discs 26.

60 Disposed upon the top surfaces of barium titanate discs 26 adjacent the silver electrodes 27 is still another solid steel block 30 of the same dimensions as the block 12. A bore 31 extends through the width of the block 30 at the center thereof. Affixed to the side

65 32 of the block 30 is a metal conductor lug 33 which is secured to the side 32 of metal block 30 in a manner to secure good electrical contact therebetween by means of a straight metal drive screw 34.

As may be seen in FIGS. 3 and 4, the transducer when assembled comprises the steel blocks 12, 19 and 30 in superposed relation with the central bores 13, 20 and 31 in axial alignment. Sandwiched between the steel blocks

12 and 19 are the four barium titanate discs 15, and, likewise, sandwiched between the steel blocks 19 and 30, are the barium titanate discs 26. An epoxy cement 35 having contained therein a conducting medium such as very finely-divided solder powder, or similar conducting material, secures the silver electrodes 17a, 17b, 17c and 17d to the surface 14 of the steel block 12 and the silver electrodes 16a, 16b, 16c and 16d to the bottom surface of the steel block 19. Similarly, the epoxy cement 35 with finely divided conducting medium secures the electrodes 28a, 28b, 28c and 28d of the barium titanate discs 26 to the surface 25 of the steel block 19 and also the silver electrodes 27a, 27b, 27c and 27d to the bottom surface of the steel block 30.

As may be seen in FIG. 4, electric current-carrying wires 36 and 37 are connected to the lugs 33 and 22 respectively. As indicated diagrammatically in FIG. 4, the electrical current-carrying wire 36 is grounded, as is also the metallic membrane 10. Electric current-carrying wire 37 is provided for the input of electric current from a power source (not shown) capable of generating radio frequency electrical energy.

A modification of the transducer as provided in accordance with this invention is illustrated in FIG. 6 in which the brazing 11c between the metallic membrane 10 and the solid steel block 12 has been replaced by the epoxy cement 35 and still another conductor lug 39 is secured to the side 40 of the block 12 by a straight metal drive screw 41 so that good contact is made between the lug 39 and the block 12 for the passage of electricity. In the modified arrangement of the transducer illustrated in FIG. 6, the electric current-carrying wire 36 leading from the lug 33 is connected to the ground wire 42 which is in turn attached to the lug 39 affixed to the block 12. As in the previous form of the invention, the electric current-carrying wire 37 leads from the lug 22 affixed to the block 19 to a source of radio frequency electrical energy (not shown).

It is an important characteristic of the transducer as provided in accordance with this invention that the nodal zone of the stack falls within the block 19. While any convenient method of assembly of the transducer stack may be used which meets the requirement that the nodal zone of the transducer falls within the middle block of the stack, a preferred method of assembly is as follows:

The steel block 12 is sandblasted on the top side thereof and thoroughly cleaned. The steel membrane 10 is thoroughly cleaned to remove all oil and loose particles after which the block 12 is spot welded to the steel membrane 10 in two or more spots, leaving the sand blasted side of the block 12 upward. Prior to the cleaning of the block 12, the hole 13 is drilled and tapped in the center of the block for the reception of a threaded cap screw. Both sides of the block 12 are carefully freed of burrs and the like. A slug of copper is then dropped into the tapped hole 13 and the unit is placed in the furnace. After sufficient heat has been applied to deoxidize the block 12 and the steel membrane 10 and to melt the copper, the block 12 is thoroughly brazed to the steel membrane 10 by the melted copper which completely fills the void between the block 12 and the aforesaid membrane. Barium titanate discs 15a, 15b, 15c and 15d having silver electrodes 16a, 16b, 16c and 16d on the upper side thereof and silver electrodes 17a, 17b, 17c and 17d on the lower side thereof are now thoroughly cleaned. A thin coating of epoxy cement 35 containing finely-divided solder powder is smeared on the discs and the discs are then placed on block 12 with a slight twisting motion to be certain that they are properly seated and that the epoxy cement has spread into a continuous film between the block 12 and the discs 15. Each of the barium titanate discs 15 is placed on the steel block 12 so that the positive electrode of each disc is opposite said block and facing upward. Prior to placing the barium titanate discs 15 on the block 12, the hole 13 is retapped in order to remove

any copper that might adhere to the threads of the tapped hole. The steel block 19 is now sandblasted on both sides and thoroughly cleaned. Prior to the sandblasting, a hole 20 is drilled in the center of the block. All burrs from both sides of the block are carefully removed. A thin layer of the prepared cement 35 is now smeared on the positive faces of discs 15a, 15b, 15c and 15d, and the block 19 is carefully placed on the aforesaid discs and seated while using a slight twisting motion to make sure that the film of cement wets the surface of block 19 and that a continuous cement film has been formed between block 19 and the discs 15. A masking sleeve 45, preferably plastic, is now inserted into the hole 20. The purpose of the masking sleeve is to prevent the cement from adhering to the cap screw during the subsequent firing operation. The second set of barium titanate discs 26a, 26b, 26c and 26d is now cemented to block 19 in the same manner as the discs 15 were previously described as cemented to the block 12, making sure that the positive electrode of the barium titanate discs 26 are facing the block 19. The positive electrodes of both sets of discs 15 and 26 are now facing each other and facing block 19. Steel block 30 having the hole 31 drilled therein is now prepared in the same manner as block 19 except that it is sandblasted only on the side which will face the barium titanate discs 26. Block 30 is then secured to the top of the second set of the barium titanate discs 26 using the epoxy cement 35 and in the same manner that block 19 was cemented to the first set of barium titanate discs 15.

A threaded cap screw 46 is now pushed through holes 31 and 20 and through the masking sleeve and screwed into the hole 13. The stack is then aligned by hand and the cap screw 46 is tightened with a torque wrench until a torque of 50 inch pounds has been reached. The assembly is then placed in an oven until the cement 35 is cured. Thereafter, the assembly is removed from the oven and the cap screw removed therefrom. As many of the transducer stacks as desired may be attached to the steel membrane 10 and if the dimensions of the stacks have been held the same, they will all operate upon the same frequency.

The frequency upon which a given stack will operate depends upon the dimensions of the steel blocks and the thickness of the metal membrane used in the assembly of the transducer stack. For example, a transducer which will give a frequency of approximately 30 kilocycles, when mounted on an 18 gauge steel membrane in the manner aforescribed, may be constructed from component elements having the following dimensions: steel blocks 12 and 30—2" by 2" by $\frac{3}{4}$ "; steel block 19—2" by 2" by $\frac{1}{2}$ "; barium titanate discs 15 and 26—1" diameter by $\frac{1}{4}$ " thick. Using the same size barium titanate discs, it is possible to construct transducer stacks of varying frequency over wide ranges by merely changing the thickness of the metal blocks 12, 19 and 30. As the thickness of the membrane increases, care must be taken in the design of the block 12 to insure that the aforementioned nodal point of the transducer stack falls within block 19. For example, if the membrane is $\frac{3}{8}$ " thick, the block 12 will be somewhat thinner than the block 30. It will be clear from the foregoing description that the steel blocks, 12, 19 and 30, themselves act as electrodes in the operation of the transducer stack as provided in accordance with this invention.

The assembly of the modified transducer stack as illustrated in FIG. 6, is preferably accomplished as aforescribed with the exception that instead of spot welding and brazing the block 12 to the membrane 10, the epoxy cement with finely-divided solder particles is substituted for the welding and brazing.

A further modification of the transducer, as provided in accordance with this invention, is illustrated in FIGURES 7 and 8 in which a relatively thin metal membrane 10f is secured by copper brazing 11f to a solid block of

Steel metal **12f** at the center of which there is provided a threaded hole **13f** extending through the width of the block. Adjacent the upper face **14f** of the metal block **12f** is a disc **15f** having thin electrodes of silver metal **16f** and **17f** secured respectively to the upper and lower surfaces thereof. A hole **24f** of dimension comparable to that of hole **13f** in block **12f**, is provided in the center of the disc **15f**.

Adjacent the silver electrodes **16f** on the upper surface of the barium titanate disc **15f** is another solid block of steel **19f** having a central bore **20f** extending therethrough at the center thereof. The length and breadth of the metal block **19f** are equal to the length and breadth of the metal block **12f** but the thickness or width of the block **19f** is preferably only about two-thirds that of the block **12f**. To the surface of a side **21f** of the metal block **19f**, there is attached a metal conductor lug **22f**, which is secured to the side **21f** by means of a straight metal drive screw **23f** in a manner so as to make good electrical contact between the lug **22f** and the metal block **19f**. Adjacent the top surface **25f** of the block **19f** is disposed a barium titanate disc **26f** having thin electrodes of silver metal **27f** and **28f** affixed to the upper and lower surfaces, respectively, of the disc **26f**. In like manner, as before, a circular hole **29f** extends through the disc **26f** at the center thereof. Adjacent the electrode **27f** affixed to the top surface of the barium titanate disc **26f** is still another solid steel block **30f** of the same dimensions as the block **12f**. A hole **31f** extends through the width of the block **30f** at the center thereof. Affixed to the side **32f** of the block **38f** is a metal conductor lug **33f** which is secured to the side **32f** of the metal block **30f** in a manner to secure good electrical contact therebetween by means of a straight metal drive screw **34f**.

The modification of the invention illustrated in FIGURES 7 and 8 may be assembled in like manner as described in the previous form of the invention. The centrally positioned holes **24f** and **29f** of the barium titanate discs **15f** and **26f**, respectively, are provided for the reception of a masking sleeve and threaded cap screw when assembling the transducer in the manner hereinbefore described in connection with the previous form of the invention.

FIG. 5 diagrammatically illustrates one manner of use of the transducer stack as provided in accordance with this invention. A transducer **50** is suspended from a radiating membrane **10** within a housing **51**, which is itself positioned within a tank **52** containing a cleaning fluid **53** substantially filling the aforesaid tank. The radiating membrane **10** provides a cover for the housing **51** which is submerged within the fluid **53** well below the level **L** thereof. A conduit **54** extends from the housing **51** to an opening **55** in the wall **56** of the tank **52** and carries electric current-carrying wires **36** and **37** attached respectively to solid metal blocks **30** and **19** of the transducer stack **50**. As represented in FIG. 5, the conducting line **36** leads to the ground. The line **37** leads to a source of radio frequency electrical energy (not shown). Submerged in the fluid **53** below the level **L** is a work piece **60** positioned within the tank so as to be acted upon by the sonic energy produced by the transducer stack **50** and its vibrating membrane **10**.

Ordinarily in the practice of this invention, work piece **60** is suspended in the cleaning fluid **53** as illustrated in FIG. 5 and the generator of radio frequency electrical energy is turned on. As a result, sonic energy, in the frequency determined by the specific construction of the transducer stack as aforescribed, is produced and radiated by means of membrane **10** so that it acts upon the work piece **60** to effect the cleaning of the portion of the work object submerged within the cleaning fluid **L**.

It will be appreciated that although this invention has been described with respect to one specific embodiment and modification thereof, the invention is in no way limited thereto. For example, the transducer stack, as pro-

vided in accordance with this invention and used in the manner illustrated in FIG. 5, need not be affixed to a radiating membrane independently of the tank with which said transducer is used. On the contrary, the transducer may be affixed to the sides or bottom of a tank constructed of suitable sheet metal to provide a radiating surface whereby the purpose of the invention may be equally successfully effectuated.

It will be apparent that a very great advantage of this invention is realized by the manner of its construction wherein the nodal zone of the transducer stack falls only within a portion of the stack occupied by a solid block of metal, thereby obviating the danger that the piezoelectric materials will rupture or break as a result of normal stress in the nodal zone.

Another important advantage of this invention lies in the manner in which transducers capable of producing sonic energy over a wide range of frequencies may be constructed by merely changing the thickness of the metal blocks used in the stack without changing or otherwise varying the quantity of piezoelectric materials used.

Still another significant advantage of the invention is derived from the fact that the driving impedance of the transducer stack as constructed in accordance therewith is much lower than the driving impedance of a solid block of piezoelectric or electro-strictive material which is of the requisite size to perform the same function. Moreover, a much lower voltage is required to drive the transducer than is otherwise required to drive any solid block of piezoelectric material heretofore used to perform the same function. As a result of the lower voltage required, fewer generator component failures due to dielectric breakdowns, and the like, are realized in the use of the transducer as provided in accordance with this invention.

It is a further advantageous feature of this invention that the quantity of piezoelectric or electro-strictive material which need to be used to obtain a given frequency is reduced to a minimum.

Although this invention has been disclosed, with reference to specific forms and embodiments thereof, it will be evident that a great number of variations may be made without departing from the spirit and the scope of this invention. For example, parts may be reversed, equivalent elements may be substituted for those specifically disclosed, and certain features of the invention may be used independently of other features, all without departing from the spirit and scope of this invention as defined in the appended claims.

Having thus described our invention, we claim:

1. An electro-mechanical transducer system for conversion of electrical energy into sonic energy, said system including a metal membrane for radiating sonic energy, said membrane having mechanically and conductively secured thereto a transducer comprised of a stack of alternating layers of metal of similar kind and of piezoelectric material secured together mechanically and conductively, the individual thickness dimensions of the metal layers being substantially greater than the individual thickness dimension of the piezo-electric layers, the two end and center layers of said stack being of said metal of similar kind, and means for applying alternating-current energy between the center metal layer and the two end metal layers of the transducer stack to cause said stack and membrane to vibrate mechanically, the thickness dimensions of said metal radiating membrane and of said layers of metal of similar kind in said transducer stack being so selected that the nodal zone of the mechanical vibration set up by the applied electrical energy falls within said center metal layer.

2. An electro-mechanical transducer system as claimed in claim 1 characterized in that said metal membrane is steel, and in that said metal layers of similar kind are steel.

3. An electro-mechanical transducer system as claimed in claim 2 characterized in said layers of steel and of

piezo-electric material are cemented together with a conductive cement.

4. An electro-mechanical transducer system as claimed in claim 3 characterized in that said conductive cement is an epoxy resin having finely-divided solder powder distributed therethrough.

5. An electro-mechanical transducer system for conversion of electrical energy into sonic energy, said system comprising a metal membrane free to vibrate for radiating sonic energy, said membrane having mechanically and conductively secured thereto a transducer comprised of a stack of alternating layers of metal and of piezo-electric material secured together mechanically and conductively, the two end and center layers of said stack being of metal, both end layers being free to vibrate along the axis of said stack, and means for applying alternating current energy between the center metal layer and each of the two end metal layers of the transducer stack to cause

said stack and membrane to vibrate mechanically, the thickness dimensions of said metal radiating membrane and of said layers of metal in said stack being so selected that the nodal zone of the mechanical vibration set up by the applied electrical energy falls within said center metal layer.
